CLAIM

The ornamental design for an incubator for eggs as shown and described.

DESCRIPTION

1. Incubator for eggs

Fig. 1.1 is a front, right and top side perspective view of an incubator for eggs showing my new design;

Fig. 1.2 is a right side elevational view thereof;

Fig. 1.3 is a left side elevational view thereof;

Fig. 1.4 is a front elevational view thereof;

Fig. 1.5 is a rear elevational view thereof;

Fig. 1.6 is a top plan view thereof; and

Fig. 1.7 is a bottom plan view thereof.

The broken lines in the drawings depict portions of the incubator for eggs that form no part of the claimed design.
